CLAIM

The ornamental design for a package of sample shipping kit as shown and described.

DESCRIPTION

FIG. 1 is a top front right side perspective view of an outer box of the package of sample shipping kit showing our new design;

FIG. 2 is a bottom rear left side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top unfolded view thereof;

FIG. 10 is a top front right side perspective view thereof with the top flap open showing inner boxes;

FIG. 11 is a top front right side exploded perspective view thereof;

FIG. 12 is a top front right side perspective view of a first inner box of the package of sample shipping kit showing our new design;

FIG. 13 is a bottom rear left side perspective view thereof; FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof;

FIG. 20 is a top unfolded view thereof;

FIG. 21 is a top front right side perspective view of a second inner box of the package of sample shipping kit showing our new design;

FIG. 22 is a bottom rear left side perspective view thereof;

FIG. 23 is a front view thereof;

FIG. 24 is a rear view thereof;

FIG. 25 is a left side view thereof;

(Continued)

FIG. 26 is a right side view thereof;
 FIG. 27 is a top view thereof;
 FIG. 28 is a bottom view thereof;
 FIG. 29 is a top unfolded view thereof;
 FIG. 30 is a top front right side perspective view of a third inner box of the package of sample shipping kit showing our new design;
 FIG. 31 is a bottom rear left side perspective view thereof;
 FIG. 32 is a front view thereof;
 FIG. 33 is a rear view thereof;
 FIG. 34 is a left side view thereof;
 FIG. 35 is a right side view thereof;
 FIG. 36 is a top view thereof;
 FIG. 37 is a bottom view thereof; and,
 FIG. 38 is a top unfolded view thereof.

The evenly broken lines in the figures represent portions of the package of sample shipping kit that form no part of the claimed design.

The unevenly broken lines in the figures represent lines for folding the boxes of the package of sample shipping kit and form no part of the claimed design.
